UNITED STATES PATENT OFFICE.

GEORGE W. MANSON, OF NEW YORK, N. Y.

DESIGN FOR A BICYCLE-FRAME.

SPECIFICATION forming part of Design No. 34,381, dated April 16, 1901.

Application filed March 19, 1901. Serial No. 51,938. Term of patent 14 years.

To all whom it may concern:

Be it known that I, GEORGE W. MANSON, a citizen of the United States, and a resident of the borough of Manhattan, in the city and State of New York, have invented and produced a new and original Design for Bicycle-Frames, of which the following is a specification, reference being had to the accompanying drawings, forming part thereof, and in

which—

Figure 1 is a perspective view of a bicycle-frame of my novel design. Fig. 2 is a side elevation of the same. Fig. 3 is a plan view thereof.

The leading or material features of my design consist in part of a pair of parallel vertical sides each consisting of a parallelogram 1 2 3 3^X, bars 1^b and 2^b, extending backward from the rear ends of the top bar 1 and bottom bar 2, respectively, uniting at their rear ends in a box 7, a rearwardly-inclined standard 1^a, extending upward from the rear upper corner of the parallelogram 1 2 3 3^X, and an inclined brace 3^b, extending from the box

7 to the top of the standard 1^a. The two parallel sides thus formed are united by horizontal cross-bars 11, 11^a, 22, and 25.

Other features of my novel design consist of forwardly-inclined standards 3^a, extending upward from the tops of the respective front posts 3 and converging to the upper end of the tubular head 4, and forwardly-inclined standards 2^a, extending upward from forward extensions of the bottom side bars 2 and converging to the lower end of said tubular head 4. Studs 12 project horizontally outward from the bends of the inclined standards 3^a, as shown.

Having thus described my invention, what I claim as new, and desire to secure by Letters Patent, is—

The design for a bicycle-frame as herein shown and described.

GEORGE W. MANSON.
